TEMPORARY BINDER

Filed Aug. 3, 1934

UNITED STATES PATENT OFFICE

1,993,810

TEMPORARY BINDER

Charles E. Sheppard, New York, N. Y.

Application August 3, 1934, Serial No. 738,168

3 Claims. (Cl. 129—13)

My invention relates in general to binders for temporarily binding or fastening together loose-leaves and it is particularly adapted to the type of such binders in which the loose-leaves are 5 releasably secured in the binder by means of detachable posts. One of the objects of the invention is to simplify the structure of the leaf securing means and its releasable locking-mechanism, so as to minimize the number of parts thereof 10 and reduce the number of manipulations which the user is required to perform in applying the device, locking it in place and unlocking and removing it. Another object in view is to so construct and arrange the post locking-mechanism 15 that its main portion may be disposed upon the exterior of the binder, so as to be readily accessible and easily operated from the exterior thereof, in locking and unlocking it, without having to open the cover of the binder. A further object in 20 view is to assemble in a handy unitary structure, the detachable binder post or posts and the major part of the locking-mechanism thereof. Another object in view is to combine the compression type of expanding mechanism with the tray style of 25 binder, so that while the expansion is effected by means of the telescoping posts, the loose-sheets ride over them and require no openings or perforations other than those for the one or more removable locking-posts, thereby avoiding 30 any indentations or cut-away places in the edges of the loose-sheets. Other objects of the invention will be noted from the detailed description hereinafter given in connection with the drawing herein.

35 The structures of the preferred forms of my invention are shown in the accompanying drawing, wherein;

Figure 1 shows a perspective view of a loose-leaf binder embodying the form of my invention 40 in which a single removable locking post is used.

Figure 2 shows an enlarged cross-sectional view of the binder shown in Fig. 1, the section being taken through the back part, on a plane indicated by the line 2—2, in said Fig. 1, the post 45 and its locking mechanism being shown in dotted lines, in position of removal or application.

Figure 3 shows a perspective view of the single binder-post with its locking-mechanism.

Figure 4 is a view of a detail, on a reduced 50 scale, of the inner edge of one of the notched and perforated loose-leaves, used in the construction shown in Figs. 1 and 2, and shows the relation of the removable locking-post and the telescoping posts.

55 Figure 5 is a view in elevation, on a reduced

scale, of the back or rear portion of a binder, in which the removable binder device is provided with two locking-posts.

Figure 6 is an enlarged vertical cross-sectional view of a portion of the back section or part, of the structure having two locking-posts.

Figure 7 is a view in horizontal cross-section, on a reduced scale, of the two locking-post structures, the plane of the section being indicated by the broken-line 7—7, in Fig. 6.

Figure 8 is a view, on a reduced scale, of the binder having the two locking-posts and the unnotched loose-leaves, spread open with the leaves un-locked and placed in an ordinary supporting rack, with the edges of the inner ends of the 15 leaves resting freely upon the set of telescoping posts.

Referring to the drawing, in which like numerals of reference designate like parts throughout, the binder comprises a back section or part which 20 consists in a back member 1, on which are adjustably mounted the expandable sides 2 and 3, which are actuated in the usual way by means of the toggle-levers 4, pivoted thereto, the levers being expanded and contracted by the movements 25 of the traveling-nut 5, which is pivoted to the elbow of the pair of levers and is moved to and fro by the screw-bar 6, which in turn is rotated by a detachable key or crank 7. The expansion mechanism is disposed within the back-member 30 1, and the nut operating screw-bar 6, is accessible to the key 7, through a key-hole 8, formed in the end of the back member, as shown in Figs. 1 and 7. Between the extension sides 2 and 3, are 35 mounted the usual telescoping-posts 9, 9, which in the construction shown in Figs. 1 and 2, lie within the notches 10, formed in the inner edges of the loose-leaves 11, when they are placed in the binder; the posts all being disposed in the same plane and being near the hinge 12, by which 40 the covers 13, 13, are attached to the respective sides 2 and 3, and as indicated by the dotted lines in Fig. 1.

45 My improved detachable locking device comprises one or more posts of the expandable type and consists in an upper tubular part 14, and a lower tubular part 14', which slides within the former. The post is mounted upon the removable member or plate 15, by means of a threaded stem 15', located upon the under side of the member and onto which is screwed the upper end of the interiorly threaded tubular part 14. A helical spring 16, is arranged within the two telescoping tubular parts 14 and 14', and a headed pin 16' is inserted within the upper end of part 50 55

- 14, with the head thereof bearing against the threaded stud or stem 15', and serves to guide the action of the spring and prevent its buckling. The spring maintains the outer part 14', extended 5 under spring pressure and it is compressed when such part is forcibly pressed within the part 14. When necessary, the post may be detached from its mounting, by unscrewing the inner part 14, from the threaded stem 15'.
- 10 In addition to the binder post 14—14', the removable member 15, which normally sets in a countersunk portion 2^a, carries upon its outer face a thin sliding latch-member or plate 17, mounted to slide thereon by means of longitudinal slots 15 18, in the latch-member, and the headed-studs 19, which are fixed upon the member 15, and also serve to keep the two members together. The side 2, of the back, is provided with a hole 20, midway of its length, for the reception of the 20 locking-post 14—14', which is passed therethrough and thence through a perforation 21, formed in each loose-leaf near its inner edge. The free end of the post when forced home into locking-position, fits into a cavity or hole 22, located in the opposite side 3, of the back, to stabilize the post, as shown in Fig. 2. The removable-member with its attached post, may be locked to and un-locked from the exterior of the side 2, of the back, by means of the outwardly projecting headed pins or studs 23, which are fixed upon the exterior of said side. When the locking fixture or device is applied to the binder, the locking-studs 23, pass up through apertures 24, in member 15, and thence through the key-hole 25 shaped slots 25, formed in the latch-member 17, so that the latter may be slid back and forth on the studs. The exterior of the latch-member, is provided with a finger engaging boss 26, for manipulating the latch-member in its sliding 30 movements.
- 40 Each of the loose-leaves or sheets 11, has its inner edge formed with notches or cut-away places 10, for receiving the telescoping-posts 9, in the form of the structure shown in Figs. 1 to 45 4, and also formed with a central perforation 21, for receiving the locking-post 14—14'. These notches assist in retaining the leaves in place when the locking-post is removed.
- 50 In the form shown in Figs. 5 to 8, the locking-device is provided with two locking posts 14^a, and the telescoping-posts 9^a, are placed well to the rear of said posts 14^a and the loose-leaves 11^a, are un-notched and provided with two perforations 21^a, for the locking-posts. This permits of the 55 un-notched edges of the leaves engaging and resting loosely against a fixed part within the back section, which part in this form consists in the set of the telescoping-posts 9^a; see Figs. 7 and 8. In Fig. 5, the latch-member 17, is shown as un-locked for removal of the locking-mechanism and freeing the leaves from the locking-posts. When the leaves are thus freed from the locking posts 60 and the compression of the sides is released, the binder may be placed in an ordinary rack or holder, which is indicated in broken-lines at 27, in Fig. 8. When the binder thus rests on its back and is spread open as shown, the contained leaves are entirely free and wholly unobstructed so that one or more may be taken out for reference or entering thereon certain memoranda, or items of account, as the case may be. In this 65 position of the binder, the un-locked leaves rest at their inner edges loosely upon a fixed part in the back section, such as the telescoping-posts 70 75 9^a, in the present structure, as indicated in Figs.

7 and 8, and each leaf is easily put back in its place after its removal. In using this form of loose-leaf, the same may be placed in a type-writing machine and typewritten thereon, without the liability of the inner binding edge of the leaf being mutilated, which often happens in typewriting on loose-leaves having their inner edges notched. This is an important advantage in the making of typewritten entries on loose-leaves used in temporary binders. In this form 10 which employs two binder posts, the locking-mechanism is constructed and operated in the same way as described in reference to the single post structure in Figs. 1 to 3. The position which the locking device assumes in applying or removing the same, is indicated in broken-lines in Fig. 2. 15

In both forms herein shown, the loose-leaves are compressed firmly together at their inner ends within the back part, by means of the expandable sides 2 and 3, when forcibly brought 20 towards each other by the action of the toggle-lever mechanism and as shown in Fig. 2. When the binder is to be opened to manipulate the leaves, the compression is released by moving the sides 2 and 3, away from each other to the desired 25 extent.

In both forms which I have shown herein, the removable member or plate is oblong and rectangular in shape and it is set in a counter-sink at 2^a, so that with the thinness of the removable-member and its latch-member, the device is practically flush with the exterior of the side 2, when the same is in operative locked position, thereby avoiding any objectionable projecting and obstructing parts upon the exterior of the binder, 30 which would tend to catch in foreign articles or mar the surface of a desk. Furthermore, the latch-member 17, retains its adjusted position when slid on the member 15, by virtue of the frictional contact between the surfaces of these 35 two flat members and without the use of a spring; the locking and unlocking of the device is accomplished by a rectilinear movement of the latch-member, instead of a swinging or hinged action, and this adds to the important advantage 40 of having a structure with non-projecting parts which remain flush with the binder sides when the device is in place and when it is being locked and un-locked.

Each end of the side 2, is provided with an 50 inwardly projecting flange 28, and likewise each end of the side 3, is provided with a similar flange 29, the flanges being in staggered relation so as to overlap each other in the expanding and contracting movements of the binder, and they serve 55 to prevent the lateral displacement of the loose-leaves, when they are un-locked and free; the side edges of the leaves being in engagement with the flanges, as indicated in Figs. 1, 2 and 7.

In applying the locking post mechanism, the 60 sides 2 and 3, are first compressed together so as to bind securely the inner ends of the leaves, then the end of the locking post is inserted in the hole 20, in side 2, and is pushed forcibly down so as to enter its end in the recess 22, and compress the spring 16, within the post. Then the removable member 15, is seated in the counter-sunk depression 2^a, and the latch-member is then slid into locking position on the studs 23. 65 The device is removed by un-locking the latch member, whereupon the spring within the post forces the post outwardly into the broken-line position shown in Fig. 2, so that it may be lifted entirely away from the binder and removed. 70 75 75

Having thus described my invention, what I claim and desire to secure by Letters Patent is:—

- 5 1. In a loose-leaf temporary binder, the combination of a back-section, a removable-member adapted to be detachably mounted upon the exterior of said back-section and provided with one or more binder posts constructed and arranged to extend across the interior of said back-section to engage and releasably bind together the loose-leaves when said member is mounted in place on said back-section, a latch-member mounted on said removable-member, and latch-keeper means mounted on said back-section for locking engagement with said latch-member.
- 10 15 2. In a loose-leaf temporary binder, the combination of a back part, a removable-member adapted to be demountably placed upon the exterior of said back-part and provided with one or more inwardly projecting binder-posts constructed and arranged to span the interior of said back-part to engage and releasably fasten together the loose-leaves when said removable-member is mounted in place on said back-part, a

latch-member mounted to slide on said removable-member, and latch-keeping projections arranged upon the exterior of said back-part so as to be engaged and disengaged by the sliding latch-member.

- 5 10 15 3. In a loose-leaf temporary binder, the combination of a back-section, a removable member adapted to be detachably locked upon the exterior of said back-section and provided with one or more binder-posts constructed and arranged to extend across the interior of said back-section to engage and releasably bind together the loose-leaves when said removable-member is mounted in place upon the exterior of said back-section, a latch-member mounted to slide on said removable-member and provided with slots for receiving latch-keeping studs, and latch-keeping studs mounted upon the exterior of said back-section so as to engage and disengage said slots of the latch-member, the said removable-member being 20 formed with apertures for receiving said latch-keeping studs.

CHARLES E. SHEPPARD.
